UNITED STATES PATENT OFFICE

JACOB LIGINSKI, OF MONTVILLE, NEW JERSEY

TOY

Application filed June 23, 1931. Serial No. 546,386.

The present invention relates to a toy and has for its object to provide a device of this nature which is exceedingly simple in its construction, inexpensive to manufacture, 5 strong and durable, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

15 In the drawings:

Figure 1 is a side elevation of a toy embodying the features of my invention.

Figure 2 is a top plan view thereof.

20 Figure 3 is a vertical transverse section taken substantially on the line 3—3 of Figure 2.

Figure 4 is a bottom plan view of the rear portion of the toy.

25 Figure 5 is a detail section taken substantially on the line 5—5 of Figure 1, and

Figure 6 is a detail view showing the pulley keyed on the shaft.

Referring to the drawings in detail it will be seen that the letter A denotes a substantially U-shaped frame formed with a cross member 5 and rearwardly diverging side members 6 which terminate in eyes 7. A shaft 8 is journalled through the eyes 7 and has a pair of wheels 9 on the ends thereof and a pulley 10 on the center thereof. Numeral 11 denotes a circular block mounted on the side members 6 of the frame 8 by means of eye fasteners 12. A shaft 14 is journalled through the center of the block 11 and on the lower end has keyed thereto a pulley 15 as indicated to advantage in Figure 5 at 16. A belt 17 is trained over the pulley 15 and over the pulley 10 and of course has its runs twisted as indicated to advantage in the drawings. Numeral 19 denotes a front wheel journalled on the cross member 5. A yoke 20 terminates in eyes 21 rockable on the cross member 5 one to each side of the wheel 19.

It will therefore be seen from the above description that as this toy is moved along

the wheels 9 upon rotation will cause the rotation of a circular plate 22 on the upper end of the shaft 14 and on the upper surface of the block 11. This plate 22 is provided with a plurality of pegs 23 so that figures 24 and the like may be mounted thereon if so desired.

It is thought that the construction, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A toy of the class described including a substantially U-shaped frame formed with a cross member and a pair of rearwardly diverging side members terminating in eyes, and a rear shaft journalled through the eyes, a front wheel journalled on the cross member.

2. A toy of the class described including a substantially U-shaped frame formed with a cross member and a pair of rearwardly diverging side members terminating in eyes, and a rear shaft journalled through the eyes, a front wheel journalled on the cross member, a block mounted on the side members, a plate rotatable on the block, a shaft engaged with the plate and journalled through the block, means operatively connecting the shaft with the rear axle.

3. A toy of the class described including a substantially U-shaped frame formed with a cross member and a pair of rearwardly diverging side members terminating in eyes, and a rear shaft journalled through the eyes, a front wheel journalled on the cross member, a block mounted on the side members, a plate

rotatable on the block, a shaft engaged with the plate and journalled through the block, a pulley on the lower end of the shaft, a pulley on the axle, and a belt trained over said pulleys.

4. A toy of the class described including a substantially U-shaped frame formed with a cross member and a pair of rearwardly diverging side members terminating in eyes, and a rear shaft journalled through the eyes, a front wheel journalled on the cross member, a block mounted on the side members, a plate rotatable on the block, a shaft engaged with the plate and journalled through the block, a pulley on the lower end of the shaft, a pulley on the axle, and a belt trained over said pulleys, a yoke straddling the front wheel and having eyes circumjacent the cross member and rockable thereon.
- 10 15

20 In testimony whereof I affix my signature.

JACOB LIGINSKI.
